UNITED STATES PATENT OFFICE.

ALPHEUS W. ALTORFER, OF PEORIA, ILLINOIS, ASSIGNEE TO ALTORFER BROS. COMPANY, OF EAST PEORIA, ILLINOIS, A CORPORATION OF ILLINOIS.

WASHING MACHINE.

Application filed January 12, 1928. Serial No. 1,770.

This invention relates to certain improvements in washing machines and it has particular reference to that type of washing machine intended for domestic or household use including reciprocating vacuum cups and especially to the type embodying a flat bottom tub or clothes container.

The principal object of the invention is to increase the life of the bottom of the tub or container, by decreasing or eliminating the possibility of the bottom responding to the pounding or downward and lifting or suction action which is created in washing machines due to the action of the reciprocating vacuum cups or other similar washing elements; by providing an annular ring either an integral part of or capable of engagement with the tub supporting frame structure or base ring which will hold the bottom having a bulged or swaged inwardly or upwardly shape over such ring giving the appearance on the inner side of the tub bottom of an embossed ring located medially of the bottom, thereby giving firmness and strength to the bottom and preventing the same from vibrating and acting in response to the actions of the washing elements in and on the water.

The invention has for a further object to provide a groove or channel in the annular ring into which the tub bottom may be pressed, thereby providing a water channel for draining purposes.

It is well known in the manufacture of washing machines that there are many ways of giving firmness or stiffness to the bottoms of the tubs or containers; such for instance, as grooving, swaging or embossing the same, preferably in different designs or shapes, all of which have had for their object to stiffen the bottom of the tub or container with relation to the side walls thereof, but such structures have failed to make a sufficient rigid contact with the tub supporting frame structure or base ring, and as a result, when used in connection with a washing machine embodying reciprocating vacuum cups or washing elements of a like character have not prevented the tub bottom from responding to the action of the pounders or vacuum cups, thereby eventually weakening the tub bottom at points of retention and causing a break or leak on account of a continued vibrating action of such bottom.

Referring particularly to the type of washing machine embodying reciprocating vacuum cups or washing elements of a like character, it will be understood that the downward or pounding stroke of the cups upon hitting the water transmits such action through the water to be absorbed by the bottom of the tub or container, and the upward or suction stroke of the cups from out of the water tends to create a vacuum and such action must be absorbed by the bottom of the tub or container. Without the use of my invention, it has been found that this combined downward or pounding stroke and upward or suction stroke has caused the tub bottom to respond to the action of the cups or pounders in the form of vibration and thereby eventually weakening the bottom of the tub or container at points of retention and causing leakage.

That the invention may be more fully understood, reference is had to the accompanying drawings, forming a part of the present description, illustrating a preferred embodiment of the invention, in which:

Figure 1 is an elevation of a washing machine, partly in section, of the vacuum cup type, showing an embodiment of the invention;

Figure 2 is a top plan view of the machine as the same would appear on the line 2-2, Figure 1, the tub bottom being partly broken to show the construction and arrangement of the invention;

Figure 3 is a vertical cross-sectional view showing a modification of the invention;

Figure 4 is a perspective view showing the groove or water channel as the same would appear on the line 4-4, Figure 5, and

Figure 5 is a top plan view, partly broken away, showing the modification illustrated in Figure 3.

Like characters of reference denote corresponding parts throughout the figures.

In the drawings, the washing machine is shown including a tub or container 1, supported by legs or standards 2, each having a caster-wheel 3. The tub or container 1 preferably rests on and is supported by a tub supporting frame structure or base ring 4, to be more fully described, and said tub or container is further provided with a removable lid or cover 5.

Passing up through the base ring or tub

supporting frame structure 4 and bottom wall of the tub or container, is a shaft 6 preferably reciprocal and rotatable or rockable, as may be desired, and 7 denotes a suitable sleeve structure for the shaft upstanding within the tub; suitable packings being provided at both ends to prevent leakage around its lower end and through the bottom of the tub or container and at its upper end around 10 the shaft into the upstanding sleeve.

Connected with the shaft 6 at its upper end is a supporting frame 8 to which are connected preferably vacuum cups or pounders 9, capable of reciprocal and rotatable or 15 rockable movement by the shaft 6 when operated by suitable means in cooperation with an electric motor, not shown.

10 designates an annular ring and as shown in Figure 1 is an integral part of the base 20 ring or tub supporting frame structure 4. It is shown preferably located approximately medially of the base ring 4 and having an upstanding portion constructed to fit snugly against the upwardly bulged ring 11 of the 25 bottom of the tub or container, resulting in the bottom of the tub or container, when placed upon the ring 10, being bulged upwardly or inwardly, as shown in Figure 1.

Figure 2 best discloses by a top plan view 30 the location of the annular ring 10 and is there preferably shown forming a part of the base ring or tub supporting frame structure 4 which is shown as being of web construction.

35 A water channel or groove 12, best seen in Figure 5, is provided in the ring 10 and is preferably arranged to be located in the same plane with the drain opening 13 located near the side walls of the tub or container 1 and 40 connected to the drain valve 14. In a washing machine embodying the invention, the tub bottom would be pressed or wedged into the groove or channel 12 of the ring 10 and provide a water channel 15 extending from the 45 center of the tub bottom to the drain opening 13, see Figure 2, thereby increasing the draining efficiency of the tub bottom.

Locating the ring 10, preferably as shown in Figures 1 and 2 to hold the bulged or 50 swaged inwardly or upwardly portion 11 in shape, it will be seen that the tub bottom has the appearance on its inner bottom side of an embossed annular ring, intercepted by a water or drain channel 15. On either side of 55 the raised portion, supported by the ring 10, the bottom fits snugly against the base ring 4 and will be understood to provide water channels to the drain opening 13 relieving an attendant the necessity of tilting the 60 washing machine to drain the same.

Figure 3 is substantially similar to Figure 1, except that a modification of the annular ring 10 is shown, preferably in the form of a separate ring unit 16 and provided with 65 depending lugs 17 to engage with and over-

lap the webs of the base ring or tub supporting frame structure 4. The ring 16 is not unlike in purpose and object the ring 10, being provided with a groove or channel 12, and is capable of detachment from the base ring 4, should it be desirable to remove the same for replacement on account of breakage.

It will be seen that with the invention applied in a washing machine, particularly of the reciprocating vacuum cup type or other similar structure, the pounding or downward stroke and the suction or lifting stroke of the cups will have no effect upon the bottom of the tub or container and will positively prevent the same from responding to the action of the cups in a vibrating action or any other action which might destroy the fitting of the bottom of the tub at points of retention and causing leakage.

The operation and function of the various parts, it is believed, have been clearly defined in the foregoing description and while the construction shown is particularly simple, efficient and economical, I do not wish to limit myself to that specific construction except as may be defined by the claims.

What I claim is:—

1. In a washing machine, a container having a bottom provided with a raised portion and a radially arranged depressed portion forming a drain, a bottom support for said container, means on said support for stiffening the raised portion of said container, said stiffening means provided with a radially disposed groove to receive said drain portion of said container.

2. In a washing machine, in combination, a container having a bottom, a supporting frame including a support for the container and an annular ring on said support provided with a radially disposed groove, said ring providing a stiffening means for the container bottom and said bottom having a radially arranged depressed portion seated in the groove of said ring, said depressed portion and the flat surfaces of said bottom constituting annular and radial draining grooves in the bottom of the container.

3. In a washing machine, in combination, a container having a bottom formed with a raised portion, a supporting frame, a web-like supporting base on the frame forming a rest for the container, and an annular ring separate from said base and disposed thereon to provide a stiffening means for said raised portion of the container bottom.

4. In a washing machine, in combination, a container having a bottom formed with a raised portion and provided with a radially 125 depressed portion forming a drain, a supporting frame, a web-like supporting base on the frame, forming a rest for the container, and an annular ring separate from said base and disposed thereon to provide a 130

- stiffening means for said raised portion of the container bottom, said ring having a groove to receive said drain portion of the container.
5. In a washing machine, a frame provided with a container support, a container having a bottom provided with flattened surfaces and a raised portion with a radial groove therethrough forming a drain, and
- 10 a stiffening means on said support for the raised portion of said container bottom and with a radially disposed groove forming a seat for said drain.
6. In a washing machine having vertically reciprocal vacuum cups and a container, in which the cups are received, said container having a bottom formed with a raised portion having curved sides located in spaced relation to the center and to the periphery of the bottom and merging into the latter, said raised portion substantially aligned with the cups so as to resist the action
- 15 of the latter, and means to rigidly support the raised portion.
7. In a washing machine having vertically reciprocal clothes pounders and a container in which the pounders are received, said container having a bottom formed with a raised portion located to align with the pounders so as to resist the action of the latter, and means to rigidly support the raised portion.
- 20 8. In a washing machine having vertically reciprocal clothes pounders and a container in which the pounders are received, said container having a bottom formed with a raised portion having curved sides and having its highest part vertically aligned with the centers of the pounders so as to resist the action of the latter, and means to rigidly support the raised portion.
- 25 In witness whereof, I have hereunto affixed my hand this 10th day of January, 1925.

ALPHEUS W. ALTORFER.
